RAILWAY SIGNALING

John M. Pelikan, Crafton, Pa., assignor to The
Union Switch & Signal Company, Swissvale,
Pa., a corporation of Pennsylvania

Application February 15, 1936, Serial No. 64,093

15 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three track sections in the rear of an occupied section. Each distinctive control is effective to cause a corresponding aspect of the wayside signals, whereby there is produced a three-block, four-indication, system of signaling.

I will describe one form of apparatus embodying my invention, and will then point out the 15 novel features thereof in claims.

In the accompanying drawings, Figs. 1A and 1B are diagrammatic views, which when placed end to end in the order named, illustrate one form of apparatus embodying my invention.

20 Referring to the drawings, the reference characters 8 and 9 designate the rails of a stretch of railway track along which traffic normally moves in the direction indicated by the arrows. These rails are divided by insulated joints 10 into a 25 plurality of track sections W—X, X—Y, and Y—Z.

Each track section is divided by insulated joints 10 into at least two subsections 1T, 2T, 3T, 4T, etc. Each subsection is provided with a track 30 circuit which includes a track battery 11 connected across the rails at one end of the subsection and a track relay, designated by the reference character R with a prefix the same as the reference character of the associated subsection, 35 connected across the other end of the subsection.

To govern the passage of trains through the stretch of railway, a wayside signal, designated by a suitable distinguishing reference character, is provided for each track section. Each of these 40 signals includes an upper unit U and a lower unit L. These units may take any one of several forms of signal mechanism such as semaphore, color light, searchlight, or position light. As here shown, each upper unit is a color light signal 45 capable of displaying a red light R, a yellow light Y, and a green light G, and each lower unit is a color light signal capable of displaying a green light G and a red light R.

Each section is provided with a polarized signal control relay designated by the reference character H with a prefix the same as the reference character of the associated signal.

Each section is also provided with two auxiliary signal control relays designated by the reference 50 characters S and HP, respectively, each with a

prefix the same as the reference character of the associated signal.

Each relay HP functions as a repeating relay for the associated H relay. For example, the relay 12HP is controlled by front contact 16 of the relay 12H so that the relay 12HP becomes energized or deenergized according as the relay 12H is energized or deenergized. Each of the relays HP is controlled in a similar manner by the associated relay H.

Each relay S is provided with a pickup circuit and stick circuit each controlled by the associated relay H. For example, the relay 13S is provided with a pickup circuit which passes from terminal B of a suitable source of energy through front contact 17 of relay 13H, reverse polar contact 18—19 of relay 13H, and relay 13S to terminal C of the same source of energy, and with a stick circuit which passes from terminal B through front contact 17 of relay 13H, front contact 20 of relay 13S, and relay 13S to terminal C. Relay 13S, therefore, will become energized whenever relay 13H is energized in the reverse direction and will then remain energized as long as relay 13H is energized in either direction. Each of the relays S is controlled by the associated relay H in a similar manner.

Each section is provided with a line circuit including a pair of line wires extending to the signal next in advance and controlled by each 30 of the associated track relays. Each line circuit, as will be explained more in detail hereinafter, is reversibly governed by two pole changers, one of which includes contacts of the relays H and HP for the section next in advance and the other 35 of which includes contacts of the relay S for the section in advance.

Each signal control relay H is connected directly to the associated line circuit.

Each signal is controlled by the associated relays H, HP, and S in the following manner: When relay HP is deenergized (see signal 15), the red lamp R of the upper unit U of that signal is lighted by a circuit which passes from terminal B through back point of contact 21 of relay 15HP 40 and lamp R to terminal C; and the red lamp R of the lower unit L is lighted by a circuit which passes from terminal B through back contact 22 of relay 15HP and lamp R to terminal C. The signal then displays a red light over a red light to indicate "stop". When relay H is energized in the normal direction and relay HP is energized, but relay S is deenergized (see signal 14), the yellow lamp Y of the upper unit U of that signal 45 is lighted by a circuit which passes from terminal 50

B through front point of contact 23 of relay 14HP, normal polar contact 24-25 of relay 14H, back point of contact 26 of relay 14S, and lamp Y to terminal C; and the red lamp R of the lower unit L is lighted by a circuit which passes from terminal B through front point of contact 23 of relay 14HP, normal polar contact 24-25 of relay 14H, and lamp R to terminal C. The signal then displays a yellow light over a red light 10 to indicate "prepare to stop at next signal". When the relay H is energized in the reverse direction and both relays S and HP are energized (see signal 13), the yellow lamp Y of the upper unit U of that signal is lighted by a circuit which 15 passes from terminal B through front point of contact 27 of relay 13HP, reverse polar contact 28-29 of relay 13H, and lamp Y to terminal C; and the green lamp of the lower unit L is lighted by a circuit which passes over the same path as 20 just traced for the lamp Y up to and including reverse polar contact 28-29 and thence through front contact 30 of relay 13S and lamp G to terminal C. The signal then displays a yellow light over a green light to indicate "approach 25 next signal at medium speed". When the relay H is energized in the normal direction and both relays S and HP are energized (see signal 12), the green lamp G of the upper unit U of that signal is lighted by a circuit which passes from 30 terminal B through front point of contact 31 of relay 12HP, normal polar contact 32-33 of relay 12H, front point of contact 34 of relay 12S, and lamp G to terminal C; and the red lamp R of the lower unit L is lighted by a circuit which passes from 35 terminal B through front point of contact 31 of relay 12HP, normal polar contact 32-33 of relay 12H, and lamp R to terminal C. The signal then displays a green light over a red light to indicate "proceed at normal speed".

40 To sum up thus far, each signal is controlled by a polarized relay H and a repeating relay HP as well as by a stick relay S, and is caused to display a stop indication when the repeating relay is deenergized; a restrictive proceed indication 45 when the polarized relay is energized in the normal direction, provided the repeating relay is also energized and the stick relay is deenergized, a less restrictive proceed indication when the polarized relay is energized in the reverse direction, provided both the stick relay and the repeating relay are energized; and a normal proceed indication when the polarized relay is energized in the normal direction, provided both the stick relay and the repeating relay are energized.

50 As shown in the drawings, the section 7T is occupied by a train K so that relay 15H is deenergized, and consequently, both relays 15HP and 15S also are deenergized. Current is now supplied to the relay 14H in the normal direction 55 over a line circuit which passes from terminal B through back point of contact 35 of relay 15S, back point of contact 36 of relay 15HP, back point of contact 37 of relay 15H, front contact 38 of track relay 6TR, front contact 39 of track relay 5TR, relay 14H, front contact 40 of track relay 5TR, front contact 41 of track relay 6TR, back point of contact 42 of relay 15H, back point of contact 43 of relay 15HP, and back point of contact 44 of relay 15S to terminal C.

60 Since relay 14H is energized in the normal direction and relays 14HP and 14S are energized and deenergized, respectively, current is now supplied to relay 13H in the reverse direction over a line circuit which passes from terminal B through 65 back point of contact 45 of relay 14S, front point

of contact 46 of relay 14HP, front point of contact 47 of relay 14H, front contact 48 of relay 4TR, front contact 49 of relay 3TR, relay 13H, front contact 50 of relay 3TR, front contact 51 of relay 4TR, front point of contact 52 of relay 14H, front point of contact 53 of relay 14HP, and back point of contact 54 of relay 14S to terminal C.

65 Since relay 13H is energized in the reverse direction and both relays 13HP and 13S are energized, relay 12H is energized in the normal direction over a line circuit which passes from terminal B through front point of contact 55 of relay 13S, front point of contact 56 of relay 13HP, front point of contact 57 of relay 13H, front contact 58 of relay 2TR, front contact 59 of relay 1TR, relay 12H, front contact 60 of relay 1TR, front contact 61 of relay 2TR, front point of contact 62 of relay 13H, front point of contact 63 of relay 13HP, and front point of contact 64 of relay 13S to terminal C.

70 Since relays 12H, 12HP, and 12S are all energized, the line circuit for the section next in rear of section W-X is supplied with energy in the normal direction over front points of contacts 65 and 66 of relay 12S, front points of contacts 67 and 68 of relay 12HP, and front points of contacts 69 and 70 of relay 12H.

75 When the train K passes out of the section to the right of location Z, relay 15H and, consequently, relay 15HP also will become energized to energize relay 14H in the reverse direction. When relay 14H is energized in the reverse direction, relay 14S will become energized so that relay 13H will be supplied with energy in the normal direction. Since relays 13S and 13HP are already energized, the signal 13 will be caused to display a green light over a red light, that is, the normal proceed indication.

80 It will be noted that the polarized relays H are of the well-known retained neutral armature type. That is, the neutral armatures of these relays will not release during pole-changing periods. This feature insures that the auxiliary signal control relay S, after having been picked up, will not release to cause an improper signal indication when the associated H relay is supplied with energy in the normal direction. For example, when the train K vacates the section to the right of location Z so that relay 13H is supplied with energy in the normal direction to provide the normal proceed indication at signal 13, front neutral contact 17 of relay 13H will not become opened to release relay 13S. This feature also insures against signal flashing and tumble-down of the signal control relays in the rear. For example, when relay 13H is supplied with current in the normal direction, the front points of its neutral contacts 17, 57, and 62 do not open. Consequently, the front contacts of relays 13HP and 13S remain closed so that both momentary flashing of the red lamps at signal 13 and momentary opening of the line circuit for section W-X is avoided.

85 The slow-releasing feature of the relays HP is provided to insure proper signal indications in the event a train moves through the stretch of railway in a direction opposite to the normal direction of traffic. That is, the slow-releasing characteristic of these relays provides a momentary opening of the line circuit to the rear to insure the release of the auxiliary signal control relay S controlled by the retained neutral polarized relay connected to that line circuit. For example, if section X-Y becomes occupied by a 90

train traveling from right to left, the relays 13H, 13HP, and 13S would all become deenergized to cause signal 13 to display the stop indication. The releasing of these relays would also supply the line circuit for section W—X with energy in the normal direction. Due, however, to the slow-releasing characteristic of relay 13HP, the line circuit would become opened a sufficient length of time to permit the opening of front neutral contact 16 of relay 12H so that auxiliary signal control relay 12S would become deenergized. It is readily apparent that if relay 12S did not become released, the signal 12 would continue to display the normal proceed indication instead of the more restrictive "prepare to stop at next signal" indication.

From the foregoing description, it is apparent that the apparatus embodying my invention provides a three-block, four-indication, signaling system which requires but two line control wires, which is free from undesirable signal flashing and tumble-down of signal control to the rear and which requires only direct current for its operation.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A railway signal system comprising a stretch of railway track divided into a plurality of track sections each having a track circuit including a track relay, a line circuit for each section including a contact of the associated track relay, a polarized relay for each section connected to the associated line circuit, a pole changer for each section controlled by the associated polarized relay for reversibly governing the line circuit for the section next in rear of the associated section, another relay for each section governed by the associated polarized relay, another pole changer for each section governed by the associated other relay for also reversibly governing the line circuit for such section next in rear, and a signal for each section governed by the associated polarized relay and by the associated other relay.

2. A railway signal system comprising a stretch of railway track divided into a plurality of track sections each having a track circuit including a track relay, a line circuit for each section including a contact of the associated track relay, a polarized line relay for each section connected to the associated line circuit, an auxiliary relay for each section which becomes energized when the associated line relay is energized in the reverse direction and which then remains energized as long as the associated line relay is energized in either direction, means effective when one section is occupied to supply the line circuit for the section first in rear of such occupied section with current in the normal direction, means then effective to supply the line circuit for the section second in rear of such occupied section with current in the reverse direction, means then effective to supply the line circuit for the section third in rear of such occupied section with current in the normal direction, and traffic governing means for the stretch controlled by said polarized relays and by said auxiliary relays.

3. A railway signal system comprising a stretch of railway track divided into a plurality of track

sections each having a track circuit including a track relay, a line circuit for each section including a front contact of the associated track relay, a polarized line relay for each section connected to the associated line circuit, a stick relay for each section having a pickup circuit including a contact closed only when the associated line relay is energized by current of reverse polarity and a stick circuit including a contact closed when such line relay is energized by current of either polarity, means controlled by the line relay of each section for reversibly governing the supply of current to the line circuit for the section next in rear, means controlled by each stick relay for also reversibly governing the supply of current to such line circuit in rear, and a signal for each section governed jointly by the associated line and stick relays.

4. A railway signal system comprising a stretch of railway track divided into a plurality of track sections each having a track circuit including a track relay, a line circuit for each section including a contact of the associated track relay, a polarized line relay for each section connected to the associated line circuit, an auxiliary relay for each section controlled by the associated line relay in such a manner that the associated auxiliary relay becomes energized when such line relay is energized by current in one direction and then remains energized as long as such line relay is energized by current in either direction, means governed by each line relay for reversibly governing the line circuit for the section next in rear, means governed by each auxiliary relay for also reversibly governing such line circuit in rear; and a signal for each section caused to display a stop indication when the associated line relay is deenergized, a restrictive proceed indication when the associated line relay alone is energized normal, a less restrictive proceed indication when the associated line relay is energized reverse and the associated auxiliary relay is energized, and a normal proceed indication when the associated line relay is energized normal and the associated auxiliary relay is energized.

5. In combination, a section of railway track, a first relay governed by traffic conditions in advance of said section, a repeating relay having a slow-releasing characteristic and energized or deenergized according as said first relay is energized or deenergized, a line circuit for said section and supplied with current of one polarity or the other polarity according as said two relays are both energized or deenergized, a polarized relay connected to said line circuit and having a retained neutral armature, an auxiliary relay which becomes energized when said polarized relay is energized by current of one polarity and which then remains energized as long as said retained neutral armature is attracted, and a signal for said section governed jointly by said two last mentioned relays.

6. In combination, a rear section and a forward section of railway track, a signal for the rear section, a polarized relay for controlling said signal and having a retained neutral armature, an auxiliary relay governed by said retained neutral armature for also controlling said signal, a line circuit connected to said polarized relay, a pole changer for reversibly governing said line circuit in accordance with traffic conditions in said forward section, and means included in said pole changer for opening said line circuit for a period of time sufficient to permit the release of said re-

tained neutral armature when the forward section becomes occupied by a train.

7. A railway signal system comprising a stretch of railway track divided into a plurality of track sections each having a track circuit including a track relay, a line circuit for each section including a contact of the associated track relay, a polarized relay for each section connected to the associated line circuit, an auxiliary relay for each section, each said auxiliary relay being energized when the associated polar relay is energized by current of one polarity and then being retained in the energized condition as long as such associated polarized relay is energized in either direction, means for each section including contacts of the associated polarized relay for reversibly governing the line circuit for the section next in rear of the associated section, means for each section including contacts of the associated auxiliary relay for reversibly governing the supply of current to said first means, and a signal for each section governed by the associated polarized auxiliary relays.

8. In combination, a forward section and a rear section of railway track, a line circuit for the rear section, a polarized relay having a retained neutral armature and connected to said line circuit, another relay for the rear section, means for energizing said other relay, means governed by the neutral armature of said polarized relay for then maintaining said other relay in the energized condition, a signal for the rear section and arranged to display a less restrictive or a more restrictive indication according as said other relay is energized or deenergized respectively when said polarized relay is energized, and means governed by traffic conditions in the forward section for reversibly governing the supply of current to said line circuit and for momentarily opening said line circuit when the forward section becomes occupied by a train thereby releasing said neutral armature to cause said signal to display the more restrictive indication.

9. A railway signal system comprising a first, a second, a third, and a fourth section of railway track over which traffic normally progresses in the order named, a polarized signal control relay for each section, each said polarized relay being normally energized by current of one polarity, a neutral normally energized signal control relay for each section, means effective when the fourth section is occupied by a train to deenergize both relays of that section, means then effective to energize the polarized relay for the third section with current of said one polarity and to deenergize the neutral relay of that section, means then effective to energize the polarized relay for the second section with current of opposite polarity and to maintain the energization of the neutral relay of that section, means then effective to energize the polarized relay for the first section with current of said one polarity and to maintain the energization of the neutral relay of that section, and a signal for each section governed by the two signal control relays associated with such section.

10. A railway signal system comprising a first, a second, a third, and a fourth section of railway track over which traffic normally progresses in the order named, a polarized signal control relay for each section, each said polarized relay being normally energized by current of one polarity, a neutral normally energized signal control relay for each section, means effective when the fourth section is occupied by a train to deenergize both

relays of that section, means then effective to energize the polarized relay for the third section with current of said one polarity and to deenergize the neutral relay of that section, means then effective to energize the polarized relay for the second section with current of opposite polarity and to maintain the energization of the neutral relay of that section, means then effective to energize the polarized relay for the first section with current of said one polarity and to maintain the energization of the neutral relay of that section, a signal for the fourth section governed by the two associated signal control relays and caused to indicate stop, and a signal for the third and second as well as the first section governed by the two associated signal control relays and caused to display three distinctive proceed indications having successively less speed restrictions in the order named.

11. A railway signal system comprising a first, a second, a third, and a fourth section of railway track over which traffic normally progresses in the order named, a polarized signal control relay for each section, each said polarized relay being normally energized by current of one polarity, a neutral normally energized signal control relay for each section, means effective when the fourth section is occupied by a train to deenergize both relays of that section, means then effective to energize the polarized relay for the third section with current of said one polarity and to deenergize the neutral relay of that section, means then effective to energize the polarized relay for the second section with current of opposite polarity and to maintain the energization of the neutral relay of that section, means then effective to energize the polarized relay for the first section with current of said one polarity and to maintain the energization of the neutral relay of that section, and a color light signal for each section governed by the two associated signal control relays, said signal for the fourth section being caused to display a red light over a red light, said signal for the third section being caused to display a yellow light over a red light, said signal for the second section being caused to display a yellow light over a green light, and said signal for the first section being caused to display a green light over a red light.

12. A railway signal system comprising a first, a second, a third, and a fourth section of railway track over which traffic normally progresses in the order named, a polarized signal control relay for each section, each said polarized relay being normally energized by current of one polarity, a neutral normally energized signal control relay for each section, means effective when the fourth section is occupied by a train to deenergize both relays of that section, means then effective to energize the polarized relay for the third section with current of said one polarity and to deenergize the neutral relay of that section, means then effective to energize the polarized relay for the second section with current of opposite polarity and to maintain the energization of the neutral relay of that section, means then effective to energize the polarized relay for the first section with current of said one polarity and to maintain the energization of the neutral relay of that section, and a signal for each section governed by the two associated signal control relays, said signals for the fourth and for the third as well as for the second sections each being caused to display a different aspect to indicate that the fourth section is occupied and said sig-

nal for the first section being caused to display the normal proceed aspect.

13. In combination, a section of railway track; a signal for said section comprising a first unit 5 and a second unit, said two units each including a red and a green lamp and said first unit also including a yellow lamp; a polarized relay, a repeating relay, a stick relay, means for energizing said polarized relay in the normal direction or 10 in the reverse direction, means for energizing said repeating relay when said polarized relay is energized in either direction, means for energizing said stick relay when said polarized relay is energized in the reverse direction and for then 15 maintaining the energization of the stick relay as long as said polarized relay is energized in either direction, a circuit for the green lamp of said first unit including a normal polar contact of said polarized relay and a front contact of 20 said stick relay, two circuits for the yellow lamp one including a normal polar contact of said polarized relay and a back contact of said stick relay and the other including a reverse polar contact of said polarized relay, a circuit for the 25 red lamp of said first unit including a back contact of said repeating relay, a circuit for the green lamp of said second unit including a reverse polar contact of said polarized relay and a front contact of said stick relay, and two circuits for the red lamp of said second unit one 30 including a normal polar contact of said polarized relay and the other including a back contact of said repeating relay.

14. In combination, a section of railway track 35 divided into at least two sub-sections each having a track circuit including a track relay, a pair of line conductors each including a contact of each track relay, a polarized relay connected to

said line circuit, means governed by traffic conditions in advance of said section for reversibly governing the supply of current to said line circuit, another relay which becomes energized when said polarized relay is energized in a particular direction and which then remains energized as long as said polarized relay is energized in either direction, and a signal for said section caused to indicate a less restrictive or a more restrictive indication according as said other relay is energized or deenergized respectively when said polarized relay is energized.

15. In combination, a plurality of successive sections of railway track each having a track circuit including a track relay, a line circuit for each section including a contact of the associated track relay, a polarized relay for each section connected to the associated line circuit, an auxiliary relay for each section, each said auxiliary relay being energized when the associated polarized relay is energized in the reverse direction and then remaining energized as long as such associated polarized relay is energized in either direction, means effective when the polarized relay and the auxiliary relay are both deenergized 20 to supply current in the normal direction to the line circuit for the section next in rear of the associated section, means effective when the polarized relay is energized and the auxiliary relay is deenergized to supply current in the reverse direction to the line circuit for such rear section, means effective when the polarized relay and the auxiliary relay are both energized to supply current for the normal direction to the line circuit for such rear section, and a signal 25 for each section governed jointly by the associated polarized and auxiliary relays.

JOHN M. PELIKAN.
